ANDREW A. KRAMER, OF KANSAS CITY, KANSAS.

VENT CAP OR PLUG FOR OIL OR LIKE TANKS.

1,258,915.

Specification of Letters Patent. Patented Mar. 12, 1918.

Application filed April 11, 1917. Serial No. 161,157.

To all whom it may concern:

Be it known that I, ANDREW A. KRAMER, a citizen of the United States, residing at Kansas City, in the county of Wyandotte 5 and State of Kansas, have invented certain new and useful Improvements in Vent Caps or Plugs for Oil or like Tanks; and I do declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

My invention relates to vent caps or plugs for oil or like tanks and has for its principal object to provide a cap of this character which may be threaded into a filling opening to prevent leakage therethrough and wherein a duplex valve mechanism is contained whereby air may be admitted into the tank as required by the withdrawal of its contents, and whereby the discharge of 25 gas, generated by heating of the tank, or otherwise, is permitted.

In accomplishing this object, I have provided improved details of structure, the preferred forms of which are illustrated in the 30 accompanying drawings, wherein:

Figure I is a sectional view of a tank equipped with a cap constructed according to my invention.

Fig. II is a sectional view through the 35 cap, illustrating the duplex valve mechanism.

Referring more in detail to the drawings:

1 designates a closed tank, such as is ordinarily used on wagons or trucks for the 40 transportation of oil or the like, having a filling opening 2 at the top and a discharge pipe 3 leading from its base provided at its end with a faucet 4 which may be opened or closed to regulate the flow of liquid from 45 the tank.

The opening 2 is inclosed by an internally threaded collar 5 having a base flange 6 thereon which may be bolted or welded onto the tank body, and threaded into the collar 50 is a cap, or plug 7 embodying the present invention, whereby the filling opening is closed to prevent leakage or evaporation of the contents of the tank.

The cap 7 comprises a body 8, which may 55 be threaded into the collar 5 and has an an-

nular flanged portion 9, adapted to seat against the top of the collar to limit the inward movement of the body, and formed integrally with the cap on the top and under side thereof are bosses 10—11, wherein the 60 valve parts are located; the upper boss 10 being preferably square in horizontal cross section, so that it may be used as a wrench head to facilitate movement of the cap into or from the collar 5.

Extending through the cap bosses is a longitudinal channel 13, of varying diameter and closed at its outer and inner ends respectively by plugs 14 and 15, the plug 15 being provided with a wrench head 16 and 70 the outer plug having a groove 17 for receiving a screw driver or wrench, whereby it may be removed or adjusted in the channel.

The channel 13, adjacent its outer end, 75 comprises an enlarged chamber 18, having a valve seat 19 at its base for receiving a ball valve 20, and below the chamber 18 is a smaller chamber 21 having a valve seat 22 at its base for seating a ball valve 23.

Opening into the chamber 18 is a channel 24, which extends in a downward course from the chamber and opens to the exterior of the boss 10, and opening into the side of the chamber 22 is a channel 25 which leads 85 downwardly and opens at the base of the boss 11 to the interior of the tank. A channel 26 also leads from the channel 25 upwardly and opens adjacent the under face of the cap to the interior of the tank to permit the intake of air to the tank when the tank is filled above the opening at the base of the boss 11.

Opening to the exterior of the tank at the side of the boss 10, is a channel 28 which extends downwardly into the boss 11 and opens into the channel 13 below the ball valve 23.

Assuming that the cap is so constructed and the channels, ball chambers and valve seats so formed, in assembling the parts of 100 the device the channel 13 is closed at its lower end by the insertion of the plug 15, the balls 23 and 20 seated in the chambers 21 and 18 respectively and the plug threaded into the upper end of the channel to 105 close the latter and to prevent displacement of the balls from the valve seats.

It is apparent that with the cap so constructed and in place in the opening 5, when the contents of the tank is withdrawn 110

through the discharge pipe 3, the tendency to create a vacuum within the tank is prevented by the admission of air thereto through the channels 28-13 and 25; the ball 23 being raised from its seat 22 by external air pressure as the internal pressure is reduced by the withdrawal of the contents of the tank. When the operator checks the flow from the tank by the closing of 10 the faucet 4, the ball again resumes its seat to prevent any leakage through the channels.

If gas should be generated within the tank by heating or other causes, its escape 15 is made possible through the channels 25-13 and 24; in such case the ball 20 is raised from its seat 19 by the pressure of such generated gas to permit the escape of the gas but returns to close the channel when 20 the external and internal pressure of the tank become equalized.

It is apparent that by locating the valve parts within the cap body, valves ordinarily used and which are threaded into the cap or 25 other parts of the tank may be eliminated, and a more sightly and compact equipment is provided.

It is also apparent that by so constructing the parts leakage is prevented from the tank 30 and at the same time an outlet for internally generated gases is provided, insuring safety from explosion to those who operate the tank.

Having thus described my invention, what

I claim as new therein, and desire to secure 35 by Letters-Patent, is:

1. A cap of the character described, having a vertical channel extending therethrough and inwardly closing spaced valves in said channel, the said cap also having 40 channels leading from opposite sides of the valves to the exterior of the cap and having a channel leading from between the valves to the interior of the cap.

2. A cap of the character described comprising a threaded body having an extended boss on its outer face and having a longitudinal channel closed at its ends and provided with intermediate inner and outer inwardly closing valves; the said cap also 50 having channels leading from the exterior of the cap into the longitudinal channel at opposite sides of said valves, and a channel leading from between the valves to the interior of the cap. 55

3. A cap of the character described, comprising an annular threaded body having a peripheral flange and integral inner and outer bosses; the said cap having a longitudinal channel extending through the bossed 60 portions thereof and opening to the exterior of the cap, spaced valve seats in said channel and ball valves mounted on said seats, the said caps also having a channel opening to the longitudinal channel between 65 the valves.

In testimony whereof I affix my signature.
ANDREW A. KRAMER.
